UNITED STATES PATENT OFFICE.

FULTON GARDNER, OF CHICAGO, ILLINOIS, ASSIGNOR OF ONE-HALF TO WILLIAM E. GARDNER, OF PITTSBURGH, PENNSYLVANIA, AND ONE-FOURTH TO SEYMOUR STEDMAN, OF CHICAGO, ILLINOIS.

APPARATUS FOR SIGNALING.

1,280,705.

Specification of Letters Patent.

Patented Oct. 8, 1918.

Application filed June 22, 1917. Serial No. 176,628.

To all whom it may concern:

Be it known that I, FULTON GARDNER, a citizen of the United States, residing in Chicago, in the county of Cook and State of Illinois, have invented a new and useful Improvement in Apparatus for Signaling, of which the following is a specification.

My invention relates to apparatus for operating all kinds of electromagnetic signaling systems requiring any measure of electric current, said apparatus being responsive to the impact of sound waves.

To this end my invention consists in the novel devices and novel combination of parts or devices herein shown and described and more particularly pointed out in the claims.

In the accompanying drawings, which form a part of this specification Figure 1 is a vertical section of a device embodying my invention. Fig. 2 is a plan section on line 2, of Fig. 1. The diagram shown in connection with Fig. 1, is one form of electromagnetic signal system operative with my invention.

Like numerals in both figures refer to identical parts.

3, in Fig. 1 and Fig. 2 is the porcelain base and insulating part of an ordinary standard receptacle, such as used in electric light installations.

4, in the same figure is the screw threaded metal part of the receptacle; 20 and 21, in both figures, are metal electric conductor parts with wire terminal screws inserted.

5, is a screw threaded metal part adapted to screw into the part 4.

6, is a metal cap directly connected to part 5, and supporting binding posts 13; 7, in Figs. 1 and 2, is a porcelain part with an interior chamber and threaded upon its exterior adapted to screw into the metal part 5; 9, is the wire spool of an electromagnet, and 10, is the core of the magnet with the lower end extending through an opening in the porcelain cup part 7 and it is shown in contact with the central electrode part 21 of the receptacle. 11, is the upper end of the core 10, bored out through which to thread the lead wires from the magnet 9,

10, to the binding posts 13; 12, is a tube of insulating material surrounding the core part 11. 8, is a circular metal plate in contact with part 5, and forming a cover for the cup 7. 8^a, is a diaphragm and 8^b, are metal

points attached to the diaphragm 8^a. 14, is finely divided metal, such as iron filings within a recess, formed by the magnet core part, the flange, and the upper part of the porcelain part 7.

19, is a microphone or magnetic telephone; 18, a battery and 17 an induction coil in the microphone circuit. 15, is a circuit leading from the secondary winding of the induction coil 17, to the binding posts 13.

22, is one side of an independent signal circuit leading from the battery 23 and connected to the electrode 21, of the receptacle. The other side of circuit 22 leads from the battery 23, to the bell 24, and from the bell to screw terminal inserted in the electrode 20, thus completing the circuit through the parts 4, 5, 8, 8^a, 14, 10 and 21.

25, is a condenser bridged across the independent signal circuit, the purpose of which is obvious to persons skilled in the art.

In appearance, the part of my invention, described in detail, is that of an ordinary lamp socket or standard receptacle, with a fuse, plug, screwed therein upon which is mounted two binding posts.

The magnet 9, coherer 14, and diaphragm 8^a, within the chamber of the insulating part 7, are movable. The plug part 6, when screwed into the receptacle 4, the core 10, will be in contact with the electrode part 21. 85 The proper adjustment of the coherer granules 14, the diaphragm 8^a, and magnet 9, is obtained by regulating the compression by the screw threaded plug into the correspondingly threaded receptacle. 90

In operation my invention, assuming it is properly installed, at or near a bank vault or safe, which it is intended to protect, the sound caused by the blow of a hammer, other instruments, or explosion, would vibrate the diaphragm of the microphone, the impulse of increased current would be amplified by the induction coil, the secondary winding of which is directly connected to the magnet. This in turn will energize the magnet and the metal filings in contact with the magnet will become magnetized by induction, causing the divided metal to cohere, thereby practically closing the independent signal circuit and causing the signal devices 100 to respond simultaneously with the impact of the sound waves upon the diaphragm of the microphone. 105

The diaphragm part 8^a, mounted above the magnet will act as an armature of the magnet, the points 8^b carried by this armature extend down into the cohering metal. 5 When the electromagnet is demagnetized, the diaphragm-armature will return to its normal position, and the metal points carried by the armature will likewise react and disturb the metal particles causing deco- 10 herence, and thereby open the independent signal circuit. It is a well known fact that metal finely divided is an electric conductor of enormous resistance, but when caused to cohere by electromagnetic induction the re- 15 sistance is greatly decreased, and will admit the passage of electric current of comparatively low potential. The function of the coherer as used in my invention is similar to that of a switch to make and break a relayed 20 independent circuit and energize and actuate signaling devices, such as electric lamps, bells, gongs, spark coils, telegraph sounders, etc. It is also my purpose to use it in submarine signaling. 25 It should be understood that the structure described by this specification is illustrative only and for the purpose of making my invention more clear, and that I do not regard the invention as limited to any of the 30 particularities of construction chosen for purposes of illustration, except in so far as I have included such limitations within the terms of the following claims.

What I claim is:

35 1. A relay of the class described compris-

ing a receptacle and a plug in electric contact—one with the other, a magnet within said plug, the winding of said magnet in circuit with a microphone and a source of potential, means within said plug operable 40 by said magnet to relay and control an independent electric current for the purpose specified and substantially as described.

2. In a relay of the class described a screw threaded plug adapted to fit a screw threaded 45 socket, an insulating cup within the screw threaded part of said plug an electromagnet within said cup and an elongated core of said magnet comprising an electrode extending through an opening in the bottom 50 of said cup, and means to adjust said magnet in relation to its armature; said armature forming a cover of said cup, and in contact with the threaded part of said plug, for the purpose intended and substantially as 55 described.

3. A relay comprising a screw threaded insulating part and a screw threaded metallic part by which said insulating part and said metallic part are held together and a cap piece 60 covering both of said parts with binding posts mounted thereon through which electric current is transmitted to the winding of the relay magnet within said insulating part, and means to conduct a relayed elec- 65 tric current through the core of said magnet.

FULTON GARDNER.
